SPEAKER MATCHING AND SELECTING
DEVICEPeter J. Faber, Chicago, Ill., assignor to Mont-
gomery Ward & Co., Incorporated, Chicago, Ill.,
a corporation of Illinois

Application January 15, 1938, Serial No. 185,245

17 Claims.

(Cl. 179—1)

My invention relates to a device for matching speakers to amplifiers, and selecting certain speakers in public address systems and the like.

In the public address systems now in common use, it is frequently necessary to change the number of speakers connected to the amplifier. Since the usual practice is to use impedance adjusting transformers to regulate the impedance ratio, it becomes necessary to change the transformer connections each time a change is made in the number of speakers used in the system. An ordinary unskilled person has difficulty in determining the connections of the transformer to be used. It is generally true that for the maximum undistorted power output for any given tube (or tubes), the load impedance should be approximately twice that of the tube. Since the primary of the impedance adjusting transformer forms the load for the tube, and since the secondary of the impedance adjusting transformer must have the proper number of turns for correct power transfer from the primary to the secondary and thus to the speaker, so that the impedance of the speaker and the secondary are equal, it can be readily understood that a change in the number of speakers will destroy the balance of the system, necessitating a change in the transformer turns ratio.

It is an object of this invention to provide a device whereby additional speakers may be added by merely changing the set of an indicator pointer to a public address system already in operation and still secure proper undistorted power transfer without disturbing the wire connections to the transformer.

It is a further object of this invention to provide, in the same device, an arrangement whereby selected speakers may be used as the first series of speakers on the circuit, and additional speakers may be connected to the system from predetermined locations, as they may be needed. This is made necessary by the fact that an address system adjusted for a small crowd might have the speakers located in an advantageous point fairly close to the source of entertainment such as an orchestra or the like. As the crowd becomes larger, additional speakers farther back and in certain locations might be desirable. By merely readjusting the indicator, the speaker desired may be brought into the system in order.

Another object of this invention is the provision of an inexpensive device using a single transformer for the varied number of speakers. This eliminates the expensive additional equip-

ment now necessary to be carried wherever additional speakers are apt to be needed.

It is a further object of this invention to provide an indicator means that is easily understandable and can be quickly adjusted.

It is an object to provide a distribution box and structural connector unit having a plurality of sockets or connections and a switch control connection connecting in speakers.

It is an object to provide a plurality of tap connectors combined with matching transformers and switch controls in a speaker matching and distribution box for public address and other speakers.

It is a further object to provide a speaker distribution box having the speaker matching and selecting qualities of this invention which box may be located at some point as near the speakers as possible and does not have to be located in or near the amplifier.

It is another object to provide an arrangement whereby additional distributor boxes accommodating additional speakers may be used when desired by merely changing one contact on the distributor box when the additional boxes are added to the circuit.

Other objects and advantages of this invention will appear as the nature of the improvements is better understood, the invention consisting substantially in the novel construction and the combination and arrangement of parts hereinafter fully described, illustrated in the accompanying drawings, and finally pointed out in the appended claims.

The form of the invention herein shown and described presents a preferred embodiment thereof, and delineates its adaption to practical use. It is to be understood that the present disclosure is to be considered from the illustrative standpoint and not as imposing restrictions or limitations on the invention.

In the drawings:

Figure 1 is a perspective view of the external arrangement of the box embodying the present invention, showing the top, front and one end of the box.

Figure 2 is a plan view taken on the line, 2—2 of Figure 1, looking in the direction of the arrows.

Figure 3 is a circuit diagram showing the speaker matching and selecting circuit used in this invention.

Figure 4 is a modification of the diagram of Figure 3, the speaker selecting contact being omitted.

Figure 5 is a circuit diagram showing a plu-

rality of the speaker matching and selecting devices connected in parallel on a 500 ohm line from the amplifier.

Figure 6 is a modification of the diagram of Figure 3 showing the transformer primary with leads or taps to the amplifier.

Referring more in detail to the construction shown in the various figures, number 10 is the box or container for the mechanism constituting this invention. This box has the front 11, the ends 12 and 13, the rear 14 and the top 15.

The front panel 11 carries a dial or indicator 16, which is shown as marked for calibrations. The switch knob 17 is located so that the turning of the knob will bring one end into line with a calibration on the dial. In this connection the knob 17 is preferably narrowed at one end to form a pointer, as shown at 18.

This pointer is a quick guide for the eye in searching for the calibration to which the knob is turned.

Each end of the box 10 carries the socket contact into which the connector cords or wires of the speakers are inserted. These sockets are numbered 19, 20, 21, 22, 23 and 24 respectively, as shown in the drawings.

I have shown at one end the terminal contacts 25, 26, 27, 28, 29 and 30 for the primary side of the transformer 31. To protect these contacts 30 and to protect the operator from shocks, I have provided the cover plate 32, which is held in place by small bolts and nuts 33. The transformer 31 is preferably the universal type of transformer in general use, and a very good transformer has 35 a primary with taps of 500 ohms, 1000 ohms, 1500 ohms, 2000 ohms, and 2500 ohms, and a secondary with taps of 500 ohms, 8 ohms, 4 ohms, 2½ ohms, etc. It has the core 34, windings 35, and is suspended from the top 15 by means of 40 bolts and nuts 36. The switch 37, is operated by the switch knob 17. To assure proper and accurate contact, the switch is provided with the guide disk 38 which is notched at intervals around its periphery. The spring 39 contacts and maintains a tension on the notches, thus keeping the switch in proper alignment. These notches are 45 preferably located so that pressure of the spring 39 will bring the pointer 18 into alignment with the calibrations on the dial 16.

The various leads 40, 41, 42, 43, 44 and 45 from the secondary taps of the transformer are arranged for proper contact by the switch 37. The connector 46 runs from the switch to one of the contacts of each socket 19, 20, 21, 22, 23 and 53 24. The other contact on each socket is the common or ground contact 47 from the secondary of the transformer 31. The sockets as shown have two extra holes, which are not essential however, but are here provided as guide holes 50 and the like. Referring in particular to the circuit diagrams, Figure 3 shows a circuit in which the speaker contacts are wired so as to be brought into use by turning switch 37 to the indicated number. As the pointer is turned clockwise, a different ratio of turns on the secondary in contacted and the sockets 19, 20, 21, 22, 23 and 24 are contacted in sequence and the contact is maintained for the first sockets contacted as the subsequently contacted sockets are brought 65 into circuit. The scheme shown in this diagram of Figure 3 makes it possible to plug in six speakers (more if the circuit is designed for more) and leave them plugged in whether it is desired to use one or all or any number of them. 70

The speakers should be arranged so that the first

one to come in, that of socket number 19, will be one that is to be used at all times when the circuit is operating. Those speakers or sockets on numbers 20, 21, 22, 23 and 24 should be those desired to be used in sequence so that they may be cut out of the circuit or cut into the circuit as desired, this result being accomplished by merely adjusting the pointer 18 of the switch 37 at the indicated number.

In Figure 4 the sockets 19, 20, 21, 22, 23 and 24 are connected in parallel. It is not intended to leave the speakers plugged into these sockets when speakers are not in use. It is immaterial which plug any particular speaker is plugged into in the arrangement shown in Figure 4, and the selector arrangement shown in Figure 3 is not present. As the individual speaker is plugged in however the pointer on the switch 37 is placed to the indicator showing the number of speakers in the circuit as shown in the diagram.

As will be evident from examination of Figures 3 and 6, the circuit shown there is adaptable for incorporation directly into an amplifier; that is, it may be adapted to take the plate current directly from the tube of the amplifier for the 25 primary, in which instance the primary taps will be changed to handle the impedance of the tube plates. The ratio of turns of the secondary to the primary would be changed so that the secondary taps would have the proper impedance 30 for the speakers.

In addition, the additional portion 48 of a circuit is provided so that the 500 ohms impedance on the transformer secondary is automatically cut out of the speaker circuit for the sockets, 19, 20, 21, 22, 23 and 24, and is directed through circuit portion 48 to the 500 ohms output terminals, where it is available for use to operate distributor box located at a distance from the amplifier or a speaker with a 500 ohms impedance 40 or any other electric device requiring a 500 ohms input. The terminal contacts 25, 26, 27, 28, 29 and 30 are provided so that additional distributor boxes may be connected to the circuit from the amplifier tube. The terminal contact 25 is considered the common contact, and the additional contacts are for variation in the number of distributor boxes. In the example shown, if you have only the one distributor box, the contact 26 which is the 500 ohm contact would be used in 50 connection with the common contact 25. If two speaker boxes were in the line, the contact 27 which is the 1000 ohm contact would be used with the common contact 25 on each. This would give a primary impedance of 500 ohms to each 55 of the two distributor boxes. As a third distributor box is added to the line then each of the distributor boxes in the line would have connections to the 1500 ohm impedance contact which is here shown as number 28, or if more than three distributor boxes are in the circuit then the 2000 or 2500 ohm contacts number 29 or 30 respectively would be used with the common. Of course, the distributor box could be wired for additional contacts but it is not considered necessary to disclose any more in this application. It will be understood, however, that where two boxes are 60 on the line, each box having the same range of impedance, the primary terminal contact used with the common primary terminal contact 25 65 would be set the same on each box.

Since the low impedance used by the ordinary speaker today—for example, eight ohms—makes it difficult to have the speaker more than thirty-five or forty feet from the amplifier tube 70

because of wire resistance and loss of power, it can readily be seen that this box has the advantage of being operable long distances from the amplifiers since the primary input is more than sufficient for the secondary output requirements of the speakers, and the wire loss is of little or no consequence. This simplifies use of the public address system in schools, factories and other places, where numerous rooms at long distances from the amplifier are in the system.

The form of invention herein shown and described is believed to be a preferred embodiment thereof, but it is to be understood that the same is susceptible to change, variation and modification in the arrangements of the parts. The form illustrated, therefore, is to be taken from the illustrative standpoint only, and not as imposing restrictions or limitations upon the invention.

20 I claim:

1. In combination a container, a universal transformer therein, input connections to the primary of said transformer, taps on the secondary of the transformer with leads to an adjustable switch means, a switch knob located outside the container with connections to the switch means whereby movement of the switch knob changes the transformer secondary contact of the switch, an indicator on said container co-30 operating with the switch knob to indicate the position of the switch, a plurality of speaker contact sockets or the like carried by the wall or walls of the container, a common tap connector from the secondary of the transformer to one contact on each of the speaker contact sockets and a lead from the switch to another contact on each of the speaker contact sockets, all of said mechanism operating to produce a load of desired impedance on the plate circuit of an 40 amplifier or the like and to give impedance output of predetermined amount, the output being variable by adjustment of switch, whereby a variable number of speakers are operated.

2. In a device of the class described, the combination of a container box, universal transformer therein with secondary taps at positions giving predetermined output, contact means for an amplifier or the like to the primary of said universal transformer, adjustable contact means 50 to a plurality of speakers from the secondary of said universal transformer, said contacting means contacting the proper secondary tap, watching the load impedance of the speakers whereby one or more speakers are operated from 55 said speaker contact means, and indicator means, in connection with said adjustable speaker contact means showing the number of speakers operable at a given time on said contact means.

3. As a unitary device, a transformer having 60 selectable input and output connections, contacts to said input connections from a plate circuit or the like, contacts from the output connections of the transformer to an adjustable switch, contact means from said adjustable switch to connections for speakers and the like, and a common connection from the secondary of the transformer to said connections for speakers and the like.

4. In a device of the class described the combination of a container, a transformer with primary taps for load impedance values in arithmetic progression, a secondary tap with outputs substantially equal to the input of the lowest primary tap, and having, also, a plurality of 70 secondary output taps, each tap of output to

match respectively the load impedance value, and switch means matching the speaker contacts and the respective secondary tap for proper output to the speakers contacts in operation.

5. In a device of the class described the combination in a unitary arrangement of a universal transformer having adjustable primary taps for load impedance values in arithmetic progression, a secondary tap with output substantially equal to the input of the lowest primary tap above 10 the common, other secondary taps with graduated output to respectively match the load impedance value of a successive number of speaker contacts, each speaker contact having substantially equal load impedance value, an output 15 contact with load impedance substantially equal to the first mentioned secondary tap, and a switch means manually operable to close the circuit between the first above mentioned secondary tap and the last above mentioned output contact 20 and operable to open said circuit and close in succession circuits between the respective secondary taps and speaker contacts substantially as described.

6. In a device of the class described transformer means having taps on the primary for input of preselected impedances and taps on the secondary for output of preselected impedances, switch means in connection with said output taps manually variable for selection of transformer 30 secondary tap having proper impedance, and contact means from said switch means accommodating a variable number of speakers.

7. In a device of the class described, the combination of a transformer having input connections and adjustable output connections, of a manually operated switch means variable to contact any one of said output connections of the transformer, corresponding contact means on the switch means contacting in sequence one or more 40 speaker contacts.

8. In a device of the class described, the combination of a transformer with primary taps for impedance values in arithmetic progression, and secondary taps for output accommodating one 45 or more speaker contacts of equal load impedance, and manually operable switch means selecting secondary tap and corresponding speaker contacts, substantially as described.

9. A speaker matching and selecting device 50 having a transformer with input contacts, each of said contacts being of different input capacity, said transformer having a tapped secondary with leads to a manually operable switch means, a plurality of connections from said manually 55 operable switch means to a plurality of speakers, and a common connection from secondary of the transformer to said speakers.

10. A speaker matching device having a transformer with a plurality of input taps on its 60 primary, each of said taps being for a different input capacity, a secondary on said transformer having output taps contactable by a variable switch means, separate contacts to a plurality of speakers from said switch means, whereby 65 movement of said switch automatically cuts into or out of circuit as the case may be, the proper number of speakers contacts matching the load of the proper output tap of the transformer secondary, all of the speakers operable by said 70 device having a common connection to the secondary of the transformer.

11. In a device of the class described a combination of the universal transformer with secondary taps in positions giving predetermined 75

- output, contact means for an amplifier or the like to the primary of said universal transformer, adjustable contact means to a plurality of speakers from the secondary of said universal transformer, whereby adjustment of the adjustable speaker contact means contacts the proper secondary tap matching the load impedance of the speakers.
12. In a device of the class described a combination of the universal transformer with secondary taps in positions giving predetermined output, contact means for an amplifier or the like to the primary of said universal transformer, adjustable contact means to a plurality of speakers from the secondary of said universal transformer, whereby adjustment of the adjustable speaker contact means contacts the proper secondary tap matching the load impedance of the speakers, and indicator means showing the number of speaker contact means at any given time in the circuit.
13. In a device of the class described the combination of a universal transformer with secondary taps at positions giving predetermined output, contact means for an amplifier or other sources of current, switch means adapted to contact in sequences the taps of the transformer secondary giving increased amounts of output, said switch means being likewise adapted for contacting and maintaining contact with a plurality of speakers contacts, whereby certain preselected speakers are brought into the circuit successively by operation of the switch means, while maintaining contact with the speakers previously brought into the circuit, said switch means automatically contacting the proper tap of the secondary to match the load of the speakers then in circuit, and a given connection from the secondary to the speakers.
14. In a device of the class described the combination of a universal transformer with secondary taps at positions giving predetermined output, contact means for an amplifier or other sources of current, switch means adapted to contact in sequence the taps of the transformer secondary giving increased amounts of output said switch means being likewise adapted for contacting and maintaining contact with a plurality of speakers contacts, whereby certain preselected speakers are brought into the circuit successively by operation of the switch means, while maintaining contact with the speakers previously brought into the circuit, said switch means automatically contacting the proper tap of the secondary to match the load of the speakers then in circuit and a given connection from the secondary to the speakers, and indicating means indicating the speakers in circuit at any particular time.
15. A speaker matching and selecting device, having a transformer with a plurality of input contacts, of respective values giving an impedance increase of substantially equal predetermined amounts; source of power; a plurality of said speaker matching and selecting devices connected to said source of power in parallel, the common contact of each of said speaker matching and selecting devices being connected to one lead from the power source, and an input contact on each of the devices having a value that when divided by the number of devices in the circuit substantially equals the impedance value from the source of power, being connected to the other power lead.
16. A speaker matching and selecting device having a transformer of input contacts arranging from 0 to a number derived by multiplying the impedance of the power source by the number of speaker matching and selecting devices in the circuit, each of said contacts having a greater impedance increase than the last contact by an amount equal to the impedance of the power source, whereby when the common contact of each speaker matching and selecting device is connected to one lead, the proper contact connected to the other lead on each of said speaker matching and selecting devices, is determined by multiplying the impedance of the power source by the number of speaker matching and selecting devices in the circuit.
17. A speaker matching and selecting device having a transformer of input contacts arranging from 0 to a number derived by multiplying the number 500 by the number of speaker matching and selecting devices in the circuit, each of said contacts having a greater impedance increase than the last contact by an amount equal to the impedance of the power source, whereby when the common contact of each speaker matching and selecting device is connected to one lead, the proper contact connected to the other lead is determined by multiplying the impedance of the power source by the number of speaker matching and selecting devices in the circuit, and the matching of each speaker matching and selecting device upon placing an additional speaker matching and selecting device into the circuit is accomplished by moving the last mentioned contact on each of the devices in the circuit up one tap.
